UNITED STATES PATENT OFFICE

2,224,613

MANUFACTURE OF WELTED FOOTWEAR

John Frederick Smith, Quincy, Mass., assignor to
 Compo Shoe Machinery Corporation, Boston,
 Mass., a corporation of Delaware

Application March 2, 1938, Serial No. 193,455

3 Claims. (Cl. 12—142)

This invention relates to the manufacture of footwear, and more particularly to shoes having a welt incorporated therein by "staple-stitching."

General objects of the invention are to provide 5 a novel form of welting which is especially suitable for "staple-stitching" attachment to other shoe parts, and to provide improved shoemaking methods and constructions involving use of such welting.

Some particular objects of the invention are to 10 provide a pre-prepared welt having a cementable retaining thread adhesively anchored lengthwise therealong in position to be straddled by staples insertable by a conventional stapling machine, 15 and to provide methods of making shoes in which such welt can be easily and firmly incorporated by using such a conventional machine.

Other objects of the invention will in part be 20 obvious and will in part appear hereinafter.

The invention accordingly comprises the several steps and the relation of one or more of 25 such steps with respect to each of the others, and the article possessing the features, properties, and the relation of elements, which are exemplified in the following detailed disclosure, and the scope of the invention will be indicated in the claims.

For a fuller understanding of the nature and 30 objects of the invention, reference should be had to the following detailed description taken in connection with the accompanying drawing, in which:

Fig. 1 is a fragmentary perspective view of a 35 portion of welting embodying features of the invention;

Fig. 2 is a transverse sectional view across the 40 forepart of a lasted upper adapted to have welting of the present invention attached thereto;

Fig. 3 is a perspective view showing the fore- 45 part section of a shoe having the welting of Fig. 1 attached; and

Fig. 4 is a transverse sectional view across the 50 forepart of a completed shoe.

The present invention relates generally to a 55 type of welted shoe illustrated, for example, in U. S. Patent No. 1,737,484 issued November 26, 1929. In such a shoe, the upper can be easily overlasted in flat relation with the insole as for McKay or related types of shoes, this being simpler than most methods of upper lasting welted shoes. The advantages of a welt construction for attaching the outsole are then obtained by staple-fastening a welt to the lasted upper, while using a retaining cord to prevent the staples from pulling through the leather shoe parts.

The considerable strains existing between the welt and upper would make this easy stapling operation impractical without such a retaining means.

Improvements involved in this invention are, 5 in large part, concerned with facilitating this stapling operation especially as regards the association of a staple-retaining cord with a shoe construction and related savings and improvements flowing therefrom. For example, the 10 present invention provides a prepared welting having a retaining cord incorporated with it while it is in strip form, and in this form it can economically be made up and sold to many manufacturers who already have standard stapling 15 machines capable of staple-stitching welts with the present special welting.

Referring more particularly to the illustrative drawing, and first to Fig. 1, there is provided, 20 in accordance with the present invention, a prepared welt 10 of leather or other suitable material preferably capable of providing a cementable surface. The inner edge of this surface on its grain side may be beveled in the conventional manner as at 11 to facilitate handling 25 and assembly. The sole or flesh side of the welt near but spaced appreciably outwardly from its inward edge is provided with a prepared cementable cord-receiving surface which, in the illustrated preferred embodiment, comprises a gouged 30 groove or gutter 12. This gutter accommodates a strong cord or thread 13 preferably formed of flexible cementable fibers such as cotton or linen. This cord and/or the groove is preferably impregnated or coated with cement serving adhesively 35 to anchor it along the flesh surface of the welt in position eventually to be straddled by staples attaching the welt to an upper.

In cases where a cement bond between the 40 welt and outsole is contemplated, the cement used on the retaining cord 13 should preferably be like or compatible with that used for attaching the outsole. The use of pyroxylin cement for this purpose is favored as being capable of setting or drying prior to the welt attaching operations subject to reactivation just before the sole 45 affixing operation.

Instead of by gouging a groove 12, the flesh 50 surface of the welt may be locally prepared for cement-attachment with the retaining cord by roughing or scoring and, if desired, such roughing 55 may be undertaken at this time over the entire flesh surface of the welt to strengthen the cement bond with the outsole. The groove 12 is preferred, however, because it serves readily 55

to locate the cord 13 along a definite line, and also encases the cord so that it does not get in the way of parts on a standard stapling machine, and also because it, together with the cement-
5 impregnated cord, provides a cement supply which, when activated, helps provide a strong bond between the welt and outsole.

When desired, especially if the outsole is not to be cement attached, the cord may be snugly 10 sprung or anchored in the groove without cement.

The lasted upper to which such welt is adapted to be attached is preferably assembled on a last having an iron bottom 14. The shoe may 15 comprise an insole 15 having an upper 16 lasted thereto with its lasting allowance in flat overlying relation therewith. This allowance may be stitched, or else tack or staple-lasting as indicated at 17 or cement-lasting as at 18.

20 Referring now to Fig. 3, the pre-formed welting is stapled to the lasted upper and insole by means of any suitable or desired stapling machine fitted for welt work, for example, the type shown in Patent 618,027. The welt guide is ad-
25 justed so that the staples being inserted by the machine straddle the retaining cord 13 as they are driven through and clenched against the last bottom. The heads of the staples are prevented from pulling through the welt by the 30 cord, the latter making it possible to use staples simply driven from the outside of the shoe instead of through and through stitching or other forms of through and through attachment re-
quiring delasting, otherwise used to attach a 35 welt to a flat overlasted upper.

The welt, thus attached or "staple-stitched," may, if wanted, be beaten or flattened, and it may also be roughened for cement reception if this has not previously been done. A filler 19 of 40 any suitable type may be inserted in the shoe bottom, preferably just prior to such a welt roughing operation so that any of the filler ex-
tending over or stuck on the cementable welt face is roughed away.

45 An outsole 20 is next attached to the welt 10 by cementing, stitching, or the like. In the case of cement-attachment, pyroxylin cement is preferably used and the outsole is suitably roughed and prepared for bonding to the flesh surface 50 of the welt, which may be cemented or activated just prior to sole attaching. The cement bearing or cementable retaining cord also may contact this outsole to aid in forming a firm bond between it and the upper to which the cord is 55 staple-clenched.

If desired, the presently described pre-formed welting may be staple-stitched to an unlasted upper which may thereafter be pulled over and

lasted to the insole, but it is preferable, at least when cement sole attachment is employed, to have the staples clenched the cementable cord on the welt firmly to both upper and insole.

Remaining steps such as trimming, burnish-
5 ing, heelng, inserting a sock lining, etc., may be carried out as usual in order to complete the shoe.

Since certain changes in carrying out the above process, and certain modifications in the 10 article which embody the invention may be made without departing from its scope, it is intended that all matter contained in the above description or shown in the accompanying drawing shall be interpreted as illustrative and not in a limit-
15 ing sense.

It is also to be understood that the following claims are intended to cover all of the generic and specific features of the invention herein de-
scribed, and all statements of the scope of the 20 invention which, as a matter of language, might be said to fall therebetween.

Having described my invention, what I claim as new and desire to secure by Letters Patent is:

1. In a method of making footwear, the steps 25 comprising, lasting an upper to an insole, pro-
viding a free welt having a retaining cord ad-
hesively held in a groove along its sole side, then, without delasting the shoe, feeding the 30 lasted upper and welt past a stapling machine in position to have the staples inserted by such machine straddle said cord, operating said ma-
chine to staple attach said welt, upper and in-
sole with staples having their heads engaging and held by said cord, and attaching an outsole 35 to said welt.

2. In a method of making footwear, the steps comprising, lasting an upper to an insole, pro-
viding a free welt, cementing a retaining cord 40 along the sole side of said welt, then driving staples through said welt and into said lasted upper and insole with their legs straddling said cord and their heads engaging it, providing an outsole, and cementing said outsole to said welt and cord with cement compatible with that pre-
viously used to attach the cord to the welt.

3. In a method of making footwear, the steps comprising, lasting an upper to an insole, pro-
viding a free welt having a groove along its flesh 50 side, fastening a retaining cord in said groove with pyroxylin cement, then driving staples through said welt and into said lasted upper and insole with their legs spanning said cord and their heads engaging it, providing an out-
sole, and cementing said outsole to said welt and 55 cord with pyroxylin cement.

JOHN FREDERICK SMITH.
